JAMES H. FOOTE, OF CINCINNATI, OHIO.

SASH-PULLEY.

1,361,240.

Specification of Letters Patent.

Patented Dec. 7, 1920.

Application filed February 2, 1920. Serial No. 355,806.

To all whom it may concern:

Be it known that I, JAMES H. FOOTE, a citizen of the United States, residing at the city of Cincinnati, in the county of Hamilton and State of Ohio, have invented new and useful Improvements in Sash-Pulleys, of which the following is a specification.

My invention relates to improvements in sash pulleys and the like and more particularly to the form and manner of arrangement of their housings and the adaptation of their structural elements for securing such pulleys in mounting frames differing in relative thickness; the object of the present invention being, first to produce an inexpensive housing embodying means both simple and efficient whereby it may be easily and quickly inserted in its mounting frame and securely held therein; second, to so form, and assemble in mobile and coöperative relation, the individual structural elements of the housing as to adapt them to function for this purpose without in any way detracting from the efficiency of the housing in functioning; as a support and a hood for the sheave and the chain, cord or ribbon in its passage over it; third, to provide a housing, without the embodiment of any additional element, that may be depended upon to so function with proper efficiency without regard to variations in relative thickness of the mounting frames provided for its reception, thus nullifying all objection to the abandonment of screws or similar securing devices, keeping down the manufacturing cost of the window frame by obviating any necessity for the exercise of especial care in the selecting and machining of the material used in its construction and reducing the production cost of the pulley by minimizing the different sizes required; fourth, to furnish a pulley that may be positioned and secured in its mounting frame at the building as readily and inexpensively as at the mill while the frames are in process of construction, which is of considerable economic importance as it militates against the loss from accidental damage and undue exposure to the weather to which pulleys installed in the mill are subjected between the time at which the window frames are delivered at the building and that at which the sash are hung and admits of the ready removal of a damaged or defective pulley and

its immediate replacement by a sound one 55 without disturbing the integrity of the framing.

These and other objects, I attain by mechanism such as illustrated in the accompanying drawings, in which;

Figure 1 is a view in rear elevation of the housing; Fig. 2 is a sectional view taken in the vertical plane indicated by the dotted line 2—2 of Fig. 1, showing the housing mounted in proper position in the window 60 framing with a sheave indicated in dotted lines journaled in it and the relative position assumed by its structural elements for its insertion in the framing shown by indicating the position of one of them in dotted 65 outline; Fig. 3 is a sectional view taken on the dotted line 3—3 of Fig. 2 with the sheave removed and after the removal of the housing from the framing and looking toward its upper end; Fig. 4, is a similar view looking 70 toward the lower end of the housing; Fig. 5, is a view similar to Fig. 2, but showing a housing embodying the invention in a modified form, the position occupied by the sheave 75 as well as that assumed by one of the elements of the housing for inserting the pulley 80 in its mounting frame being shown in dotted outline; Fig. 6, is a sectional view taken in the horizontal plane indicated by the dotted line 6—6 of Fig. 5, looking toward the lower 85 end of the housing after its removal from the framing; Fig. 7, is a view in side elevation showing a completed sash pulley embodying the invention in a modified form 90 installed in proper clamping position in the pulley stile of a window frame, the position assumed by one of the structural elements 95 of the housing for inserting the pulley in the framing being indicated in dotted outline; Fig. 8 is a view similar to Fig. 7 but showing a pulley embodying the invention in another modified form; Fig. 9, is a view in vertical section taken on the median line of Fig. 8 100 after the removal of the sheave; Fig. 10, is a view similar to Fig. 9, but showing the housing in slightly modified form installed at the extreme upper end of the mounting frame with its upper end confined between the inner and outer walls of a recess in the head of the window frame; Fig. 11 is a view 105 in side elevation of a modified form of the pulley as it appears upon first entering the framing, which latter is shown in frag-

mentary vertical section, the sheave being shown in dotted lines; Fig. 12 is a view in median vertical section of Fig. 11, but showing the pulley after its structural elements 5 have become positioned in proper clamping relation with the framing; Fig. 13 is a view taken in the horizontal plane indicated by the dotted line 13—13 of Fig. 12 looking toward the upper end of the housing removed from 10 the framing and without the sheave; Fig. 14 is a similar view looking toward the lower end of the housing; Fig. 15 is a view in side elevation of a modified form of the pulley properly installed in its mounting frame, the 15 position of the sheave as well as that assumed by one of the elements of the housing for inserting the pulley in the framing being indicated in dotted lines; Fig. 16 is a view in rear elevation of the housing as shown in 20 full lines in Fig. 15, after its removal from the framing; Fig. 17 is a view similar to Fig. 15 but showing the pulley in a further modified form.

Similar numerals refer to similar parts 25 throughout the several views.

The sash pulley forming the subject matter of the present application is a distinct improvement over the forms heretofore employed, having for an object the saving of labor, in installing, by the avoidance of 30 screws and similar securing devices, and embodies new and improved principles and details of construction relating more particularly to the mobility of its structural 35 elements, their form and manner of arrangement in co-operative relation, whereby provision is made for the practical application of the device to window framing of widely variable relative thickness and its 40 field of utility immeasurably increased; and while, for convenience in illustration, I have utilized a fragment of the pulley stile of a wooden or "kalamein" window frame, it will be understood that my improved housing is intended for use in all frames in which pulleys are a requirement without regard to their character, use to which they 45 are to be put or the material employed in their construction, and while I have shown the structural elements of my improved 50 housing as formed of cast and sheet metal and ordinary wire, it will also be understood that these elements or either of them may be formed in whole or part, by other 55 means than cast or sheet metal or wire by well known processes now in common use, and that particularities of material or construction relating to the sheave, nature of its bearing, etc., are not material in so far 60 as the present invention is concerned.

Referring to the drawings, the supporting element A of the housing comprises a front plate 33 having an opening 4 for the passage of a sheave 18 and a pair of rearwardly extending, substantially parallel,

side walls 5—5, preferably of less length than front plate 33 to confiningly support the ends of an axle 17 upon which the sheave 18 is journaled between them and which are connected at their lower ends by 70 a cross wall 26 to provide a base for the housing to rest upon in its mounting frame 7, and if desired, walls 5—5 may be connected at their upper ends to form a cross wall 23. 75

Upon an angle to the perpendicular on a line spaced back somewhat from its rear edge, each of the side walls 5—5 is bent out at an angle and turned back in a plane parallel to itself to form the bottom 9 and 80 outer wall 10 of a narrow forwardly facing channel 31 to provide a pair of confining runways for the rear edges 22 of the side walls 12 of a second structural element B of the housing, a hollow shell having an 85 open front and rear of substantially rectangular configuration for the unobstructed passage of sheave 18 when rotatably mounted within it and comprising a pair of side walls 12 connected at their upper ends by 90 a cross wall 14, to form a hood to shield the sheave and guard against dislodgment of the chain, cord or ribbon in its passage over it, and which is provided with an opening 15 for a purpose that will presently appear, while at their lower ends side walls 12 may be connected to form a cross wall 16, if desired. 95

The front edges 11 of side walls 12, element B, preferably occupy a plane somewhat in advance of that in which the front edges of cross walls 14 and 16 lie and to which they are preferably beveled back at their upper and lower ends to facilitate driving or sinking them into the framing, 100 as may be necessary in clamping the housing in a pulley stile of excessive thickness, and is generally preferable as increasing the frictional resistance of the parts to retrograde movement, and these edges are 110 shown as embedded in Fig. 2.

The parallel side walls 12 of element B have their straight front edges 11 positioned in substantially the same vertical plane while the rear edges 22 of these walls for 115 a considerable part of their length are beveled at an angle corresponding to that of the bottoms 9—9 of channels 31—31, element A, also in these side walls 12 a suitably disposed open rack may be provided 120 by punching in each a series of spaced openings the metal intervening forming the teeth 19 which are adapted to pass and successively engage the downwardly directed edge of a detent 21 consisting of a tooth 125 like protuberance extruded from each of the side walls 5—5 of element A, for a purpose hereinafter referred to.

To complete the housing, its structural elements A and B, which from the above 130

description are seen to be separate and distinct in themselves and individually adapted to provide, the one a support and the other a hood and guide for a sheave and a chain, cord or ribbon in its passage over it, are then assembled in mobile relation whereby they are adapted to function coöperatively for the purpose of securing the housing in its mounting frame and are connect-
 10 ed, united or interlocked in such manner as to be held against escapement but at the same time adapted to undergo a variety of changes in relative position by passing element B over the rearwardly extended side walls 5—5 of element A and slipping its side walls 12—12 back into the forwardly facing channels 31—31 of element A until their beveled rear edges 22 are brought to a bearing upon the inclined bottoms 9—9
 15 20 of these channels.

When in this position, it is obvious that the structural elements A and B, composing the housing, are interlocked and held against escape the one from the other, while it is
 25 equally obvious that their relative positions can be varied at will by raising or lowering element B, the upward and downward movement of which is limited only by the coming of its lower 16 or upper cross wall 14 into engagement with the sheave or a part of walls 5—5 of element A, and as during this movement their conjoined parts are brought into coöperation upon a vertical incline it is evident that these changes in relative position may take place simultaneously in substantially right angled planes and the distance intervening between the front edges 11 of side walls 12 of element B and front plate 33 of element A be increased or diminished at will by raising or lowering element B, hence the adaptability of the housing to function as a clamp and of its elements to move into clamping relation with its mounting frame, is apparent.

45 To insert the pulley and secure it by the structural elements of its housing in the framing, rear element B is first raised into the position substantially as shown in dotted outline in Fig. 2, the pulley is then inserted by passing it, upper end first, through the routed opening prepared for it in its mounting frame 7 and swinging back its lower end until the supporting element of the housing has become seated upon its base 26 in the
 50 55 frame rout with a portion of its front plate 33 in engagement with the outer side of mounting frame 7 to prevent its further inward passage through the frame rout, element B will then have passed entirely through the rout and become positioned with its front edges 11 facing the inner side of mounting frame 7 and a little to the rear of it.

The end of a lever, for instance a screw
 60 65 driver blade, is then passed through open-

ing 4 in front plate 33 of element A and beneath cross wall 14 of element B, its point slipped up through opening 15 provided as a convenient means for obtaining a purchase upon the upper side of cross wall 14, and element B is pried down for a distance that will vary in accordance with the differences in thickness of the framing met with, until the front edges 11 of its side walls 12, adjacent their upper and lower ends, are brought into engagement with the inner side of mounting frame 7 through coöperation of the beveled rear edges 22 of these walls with the bottoms 9 of the inclined channels 31 of element A against which they are adapted to slide in coöperation analogous to that of a pair of wedges driven past one another; continued downward movement of element B will now obviously result in drawing back and tightly clamping element A to the outer side of the framing while at the same time it is itself gradually clamped more and more tightly to the inner side of the framing by element A, and if prolonged, this movement will result in sinking edges 11 more or less deeply into the framing; thus it will be readily seen that uniformity in predetermined thickness of the framing is not an essential requirement for the efficient exercise of its clamping function by the housing.

In their then selected relative position, elements A and B of the housing with the mounting frame 7 securely clamped between them, are preferably held and maintained by the frictional resistance resulting from their engagement with the framing and the tight fit of their conjoined parts; if desired, however, an additional safeguard against the accidental loosening of the elements may be provided without the embodiment of any additional parts, and which may take the form of an open rack formed in side walls 12 of element B by punching a suitably disposed series of openings in each, the metal intervening forming the teeth 19, which as element B is forced down into clamping engagement with the framing, are adapted to pass and successively engage the downwardly directed edge of a detent 21, in form, a tooth like protuberance extruded from each of the side walls 5—5 of element A. As a tooth 19 of element B passes down over detent 21 of element A the side walls of the respective elements are sprung and held slightly apart until the tooth has passed entirely over the detent when the walls of the respective elements spring together again bringing the upwardly directed edge of tooth 19 into interlocked engagement with the downwardly directed edge of detent 21 thus securing element B against retrograde movement.

The pulley may readily be removed from the framing by a reversal of the operation

described for installing it and tooth 19 easily disengaged from detent 21 by slightly spreading apart walls 12 of element B.

In Figs. 5 and 6 a housing embodying the invention in a modified form is shown in which the elements are arranged for co-operative movement into clamping relation with the framing in response to the forced upward instead of downward movement of element B' and in which the beveled and straight edges of the side walls 12' of this element are shown reversed; element A' is shown as a casting to the side walls 5' of which sheet metal runways 31' formed as seen in cross section Fig. 6, are secured to become an integral part by a rivet 17' which may also serve as the axle around which sheave 18' revolves when journaled between walls 5' in position substantially as shown by dotted lines in Fig. 5; in this form element B' is shown as formed of wire heavy and strong enough to withstand the strains and sudden jars of ordinary use and which may be bent up to form a pair of substantially parallel side walls 12' having a cross connection 14' at their upper ends and each terminating at its lower end in an encircling ring for the confinement of a cross piece 16' thus completing in front and rear elevation substantially a hollow rectangle the sides of which present at their upper and lower ends backwardly curving front edges 11' and intermediately disposed straight rear edges 22'.

To complete the housing, the side walls 12' of element B' are inclosed in the runways 31' of element A' between the side walls 5' and 10' of which they are frictionally held but otherwise free to move up and down, back and forth, in sliding and swinging relation adapting element B' for impelled movement into clamping engagement with the framing when the pulley is positioned in it for which purpose element B' is first lowered into substantially the position shown in dotted outline in Fig. 5, the pulley is then inserted in the frame rout lower end first and its upper end swung back until its inward movement through the rout is arrested by the engagement of its front plate 33', with the outer side of the framing, the end of a lever is then inserted above sheave 18' and below cross connection 14', element B', and with the sheave as a fulcrum, the element is raised into the position shown in full lines in Fig. 5; in ascending to which position element B' is wedged back by the co-operation of the upwardly and backwardly curving front edges 11' of its side walls 12' with the upper inner edge of the frame rout and its lower end brought forward into engagement with the framing through the co-operation of the rear edges 22' of these walls 60 with the bottoms 9' of runways 31' of ele-

ment A' and tends to carry back this element also, which movement, however, is resisted by the engagement of a portion of its front plate 33' with the outer side of mounting frame 7', resulting in tightly wedging element B' between the bottoms 9' of runways 31', element A' and the inner side of mounting frame 7' and bringing the elements of the housing into substantially the relative position shown in full lines Fig. 5, 75 with the mounting frame clamped between them.

In this modified form it will be appreciated that in clamping a relatively thick pulley stile the resistance of the front edges 80 11' of walls 12' of element B' to sinking into its inner side may increase to a point at which the strain will be such as to cause these walls to yield and become permanently bent back out of normal thus facilitating the clamping under strain of stiles differing widely in thickness and as the opposing forces when the elements have arrived in clamped position are directed in planes at right angles to the co-operating 90 parts they will have no tendency to loosen under strain, while accidental impact by the sash weight on the lower end of element B' would tend to tighten, instead of loosen, the clamping grip of the housing on the framing.

Fig. 7, illustrates a housing embodying a modified form of the invention in which element B² in response to impelled upward movement is co-operatively advanced into 100 clamping relation with the framing by intermittent forward movement by means of a series of stepped vertical risers 22^a and short connecting inclines 22^b which constitute the rearwardly directed edge of an 105 elongated, vertically inclined slot cut in each of the side walls 12² of element B² and which are adapted successively to pass in mobile engagement between the side walls 5² and 10² of channels 31² a suitably disposed bearing 32 raised somewhat from the bottoms 9² of these channels, thus adapting the elements of the housing to undergo change in relative position in a manner by a turning or swinging as well as sliding movement of element B².

The process of installing this modified form consists in first lowering element B² to the position indicated by dotted lines, inserting the pulley in the frame rout lower end first, swinging back the upper end into the rout and prying up element B² into some such position as shown in full lines in the drawing, it being obvious the element will arrive in its selected clamping position in a relatively thick hanging stile with less up travel than will be required for one of less thickness.

In this as in the form just described the elements are safely held in the relative po-

sition selected for clamping the window framing by the frictional resistance of their coöperating parts to which the clamping strains act in relatively perpendicular 5 planes the only tendency toward retrograde movement being that contributed by the weight of element B² which is negligible by reason of its relative insignificance and accidental impact by the sash weight would 10 simply urge the pulley housing to clamp the framing more securely.

In Figs. 8 and 9 a housing is illustrated embodying the invention in a modified form in which the structural elements of the 15 housing are movably connected by mounting element B³ upon sheave axle 17³ between side walls 5³—5³ of element A³ and adapted relatively for limited rotary or swinging movement.

20 In this form element A³ has a portion of its face plate 33³ extended to overlie a part of the framing upon its outer side adjacent the rout formed in mounting frame 7³ for the housing to seat in and its side walls 25 5³—5³ at their upper ends carried up from a point spaced to the rear of its front plate 33³ to form extensions with front edges 27 beveled to provide wedging means to retract the upper end of the housing as they 30 are driven up through the framing at the upper inner edge of the rout in mounting frame 7³ which they are adapted to engage and penetrate more or less deeply according to its thickness, thereby facilitating the inserting and proper securing of the upper 35 end of the housing in framing differing relatively in thickness, by confining mounting frame 7³ at the upper end of the rout between the rearwardly facing engaging face 40 of face plate 33³ and front edges 27 of the extensions at the upper ends of side walls 5³—5³ of element A³.

In face plate 33³ of element A³ a short length of the metal removable to form opening 4³ is left attached at the upper end of the opening and bent in at an angle to provide a pawl or detent 24 to engage a forwardly facing edge 25 of a boundary wall at the upper end of element B³ to lock the 50 structural elements of the housing in the relative position assumed by them for securing the housing and pulley in a mounting frame 7³.

In the form here shown the hooding and 55 securing element B³ is provided at its lower end with an extension 28 a forwardly facing edge 11³ of which is adapted to engage, penetrate and become embedded in the window framing upon the inner face of mounting frame 7³ adjacent the lower end of the opening routed in it for the pulley to seat in, while at its upper end in cross wall 14³ element B³ is provided with a depression 60 presenting a forwardly facing edge 29 to 65 furnish a ledge to be engaged by the point

of a screw driver or nail set as may be used to force back the upper end of element B³ to swing forward its lower end and drive the forwardly facing edge 11³ of its lower end extension 28 into the inner face of 70 mounting frame 7³ to bring the elements of the housing at its lower end into proper clamping relation with said frame to secure the pulley against inward or outward movement therein and to bring edge 25 at the upper end of element B³ into interlocked engagement with detent 24 of element A³ beneath which the upper face of cross wall 14³ is adapted to slide in upwardly springing engagement as the upper end of element B³ 80 rotates backwardly into locking position within element A³.

To install this modified form of pulley in window framing element B³ of the housing is first swung forwardly at its upper end 85 out through opening 4³ in front plate 33³ of element A³ into substantially the position shown in dotted outline in Figs. 8 and 9; and the pulley inserted in a rout in the hanging stile 7³ upper end first, the said 90 stile adjacent the upper end of the rout entering between the forwardly facing edges 27 of the upper end extensions of side walls 5³—5³ of element A³ and the rearwardly facing engaging face of its front 95 plate 33³.

The pulley is then swung back into seated position in the window framing during which movement the supporting element of the housing is driven upwardly by the engagement of its base 26³ with the bottom of the rout and its upper end extension faces 27 driven more or less deeply up through hanging stile 7³ on its inner side thus securing the pulley against inward or outward 100 displacement at its upper end irrespective of a considerable range in thickness of the hanging stile.

Element B³ is then rotated bringing its upper end back through opening 4³ within 110 element A³ and the forwardly facing edges 11³ of its lower end extension 28 into engagement with the inner face of hanging stile 7³ into which it is driven more or less deeply relative to the thickness of the particular hanging stile engaged by driving back element B³ at its upper end until the boundary edge 25 at its upper end has arrived at the inwardly facing edge of detent 24 which then springs down into engagement with edge 25 and locks the housing elements in the relative position then assumed in clamping engagement with hanging stile 7³ releasably securing the pulley in the framing, in substantially the position shown in 115 full lines in Figs. 8 and 9.

In Fig. 10 a housing embodying the invention in a substantially similar modified form to that shown in Figs. 8 and 9, is shown installed at the extreme upper end of 120 125 130

mounting frame 7⁴ with its upper end confined and secured against inward and outward movement between the front and rear walls of a recess 34 in the head 30 of the 5 window framing instead of its being held against such movement by confining a portion of the mounting frame within a forked extension at the upper end of the supporting element of the housing.

- 10 In this instance also base 26⁴ is shown as flat instead of semicircular and disposed upon a rearwardly ascending incline, while detent 24' is shown as a spring pawl mounted at the upper end of element B⁴ and adapted 15 to engage successively the teeth 25' of a suitably disposed ratchet formed integral with element A⁴, the arrangement being such as to facilitate the inserting and securing of the housing and pulley in window framing 20 of relatively variable thickness by reason of its operating in a manner to obviate to a degree the driving of edges 11⁴ of extension 28' at the lower end of element B⁴ into the inner face of mounting frame 7⁴ thus minimizing the force required to bring the 25 elements of the housing into locked engagement to secure the pulley in the framing.

Aside from these slight modifications in form and arrangement the structural elements of the housing as well as the operation for installing it in the window framing are essentially the same as for the form last described.

- In Figs. 11 to 14 inclusive a housing embodying the invention is shown comprising a supporting element A⁵ having a centrally apertured face plate, base and side walls and a hooding and securing element B⁵ which to facilitate inserting and bringing the 40 structural elements of the housing into securing engagement with the window framing, is made extendible by a form of construction consisting in uniting a pair of suitably formed units in mobile relation the 45 one forming the upper or hooding end of the element being adapted to slide in and out in frictionally resistant telescopic relation with the unit forming its lower end and which is pivotally mounted preferably coaxially with the sheave between the side walls 5⁵—5⁵ of element A⁵ and adapted for limited rotary movement.

The upper unit of element B⁵ comprises a cross wall 14⁵ from which a pair of side 55 walls 8 descend at the front and rear edges of each of which a narrow strip of the metal is bent out and around to form the bottoms 9⁵ and outer walls 10⁵ of a pair of oppositely disposed channels to provide each 60 of walls 8 with a confining runway adapted to embrace front and rear edge portions of the side walls 12⁵ of a complementary unit comprising at its lower end a cross wall 16⁵ from which a pair of side walls 12⁵—12⁵ ascend which may be of irregular outline

except for the edge portions which are confined in the runways of its complementary unit which are straight and parallel and in a somewhat centrally disposed position in each of side walls 12⁵ a circular opening is 70 provided for the passage of sheave axle 17⁵ to admit the mounting of element B⁵ thereon between the side walls 5⁵ of element A⁵ to connect the elements of the housing in relatively mobile relation and adapt them 75 to coöperate as means for securing the pulley in window framing whether of uniform or relatively variable thickness.

To install the pulley embodying my invention in this modified form in a window 80 frame, the telescopic units composing element B⁵ are first collapsed into the relative position shown in Fig. 11, the pulley is then inserted in the rout in mounting frame 7⁵ entering its lower end first and swinging 85 back its upper end until the housing and pulley have become seated as shown in Fig. 11, the point of a screw driver blade is then placed against the forwardly facing edge of the opening 15⁵ in cross wall 14⁵ of the 90 unit forming its upper end and element B⁵ at this point is pressed backwardly which causes its lower end to rotate forwardly into engagement with the inner side of mounting frame 7⁵ adjacent the lower end of the 95 rout in which the housing is seated, then utilizing the screw driver as a lever with the sheave as a fulcrum element B⁵ is drawn out into extended position as shown in Fig. 12.

Further drawing apart of the units forming element B⁵ being prevented by a detent 100 13 carried by one of them and adapted to engage an edge at the upper end of a bottom 9⁵ of the confining runway of its complementary unit.

In drawing out element B⁵ into extended position the forwardly projecting extensions at the upper end of its side walls 8 are brought into penetrating engagement with the framing at the upper end of the rout in 110 mounting frame 7⁵ and at a depth from its inner side dependent upon its thickness and as the forwardly directed edges 11⁵ of these extensions are beveled back at their upper ends they operate with a tendency to wedge 115 and drive back element B⁵ at its upper end thus causing its lower end to exert ever increasing pressure against the inner side of mounting frame 7⁵ thereby retracting the housing and pulley in the framing and securing it therein with the structural elements of the housing in gripping relation with opposite sides of the mounting frame by the extension of element B⁵ into coöperative engagement therewith.

Element B⁵ is frictionally maintained in extended position and it is obvious that by a reversal of the operation described for installing it the pulley may be removed from the framing.

In Figs. 15 and 16 a modified form of the invention is illustrated in which the telescoping unit of element B⁶ is shown as formed of a single piece of wire while the pivotally mounted unit is shown with its side walls 12° connected for a part of their width by a cross wall at their upper as well as by one at their lower ends to better enable them to resist spreading and enhance their efficiency 10 in preventing the escape of the chain or cord from the sheave groove.

The units forming element B⁶ are assembled in telescopic relation by inclosing portions of walls 8' of the sliding unit in runways formed in the side walls 12° of the swinging unit by cutting spaced slots 20—20 and drawing out the metal between them as shown in the drawing.

The operation of installing this modified form of pulley in the framing is substantially the same as for the form last described but in coming to position in a relatively thick mounting frame the walls 8' of the telescoping unit may become permanently 25 bent back somewhat from normal enabling the elements of the housing to clamp under initial strain framing of a relatively wide diversity in thickness without impairing the strength of walls 8' or altering their suitability for resisting the strains of ordinary 30 usage to which they may subsequently be put and without necessitating the application of undue force in drawing out the telescoping unit.

In Fig. 17 a modified form of my invention is illustrated in which the complementary units constituting element B⁷ are assembled in reverse position to that occupied in the form just described.

The telescoping unit in this instance is shown as formed of ordinary wire and with each of its side walls 8² inclosed and adapted to slide in a runway 31⁷ formed at the rear edge of each side wall 12⁷ of the swinging unit by bending around a tongue of the metal in manner and shape substantially as for a hinge joint.

The pulley in this form is installed and secured in the framing in substantially the same manner as for the two forms last described except that it is inserted in the frame rout upper end first and that the telescoping unit is forced out by a downward movement.

From the above disclosures it will be readily seen that a housing for sash pulleys and the like is provided the structural elements of which without the employment of additional means or in any way interfering with the requisite supporting and hooding feature of such housings are suitably adapted to secure the housing and pulley in window framing the mounting frames of which may be of either uniform or relatively variable thickness the resulting advantage be-

ing to open for the housing and pulley a broad field of utility which would remain closed were its successful use contingent upon any degree of uniformity in predetermined thickness of the mounting frames provided for it to seat in.

Of course other means may be employed to form a sheave housing embodying requisite supporting and hooding features from a pair of elements assembled in relatively mobile relation and adapted to function as a clamp to secure the housing in its mounting frame, and it will be observed that in the forms shown in Figs. 2 and 17, without other change than the assembling of the elements loosely, instead of having to be pried down elements B and B⁷, respectively, impelled by the force of gravity alone, will drop into proper clamping position after passing through the frame rout when the pulley is seated and in a manner and to a degree in the forms shown in Figs. 5—7—11—12 and 15 the same result would follow were the elements of the housing assembled loosely and with elements B'—B²—B⁵— and B⁶ respectively, in inverted position, and these and other modifications to which the invention is equally susceptible need not be illustrated as modifications within the spirit and scope of the invention as pointed out in the claims will be obvious to those skilled in the art.

What I claim as new is:—

1. A sash pulley comprising a sheave, a housing member constituting a journal support for the sheave, and a housing member constituting a hood for the sheave, said members being relatively movable and adapted thereby to releasably lock the housing members into engagement with a rout in a window frame.

2. A sash pulley comprising a sheave, a pair of housing members relatively movable to thereby releasably lock the sheave housing to a window frame, one of said members serving as a journal support for the sheave, and one of said members serving as a hood for the sheave.

3. A sash pulley comprising a sheave, a pair of housing members to serve respectively as a journal support for the sheave and a hood, and to seat in a rout in a window frame, said housing members being connected together and relatively movable to thereby releasably lock the sheave housing to the window frame.

4. In a sash pulley, a housing, comprising two separate and distinct members constituting respectively a support and a hood for a sheave, means for connecting them in mobile relation to adapt the conjoined members to undergo change in relative position, whereby the pulley may be inserted in an opening routed in a window frame member, and the members of its housing moved into

clamping relation with said window frame member to secure the pulley therein, and means for releasably maintaining the housing members in the relative position selected 5 for clamping said frame member.

5. In a sash pulley, a sheave bearing housing, comprising a plurality of individual sheave supporting and hooding elements movably united in relatively mobile relation 10 and adapted, through initial manipulation, to co-operatively move into clamping engagement with a window frame member subject, comparatively, to variability in thickness, whereby the pulley may be positioned and secured in window framing relatively changeable in thickness.

6. In a sash pulley, a sheave bearing housing, comprising a pair of individual structural elements, constituting respectively a 20 support and a hood for the sheave, means for uniting them in relatively movable relation whereby the said elements are adapted, by a manually controlled movement of one of them, to co-operatively move into penetrating and clamping engagement with a window frame member subject to a relatively wide range in thickness, to bring the housing and pulley to properly seated and secured position therein, and means associated 30 with said elements for locking them in the relative position selected for securing the housing and pulley in said frame member.

7. In a sash pulley, a sheave bearing housing, comprising a plurality of distinctly individual sheave supporting and hooding elements, having vertically inclined complementary interlocking parts whereby they are movably connected in co-operative and frictional relation, simultaneously to effect 35 changes in the relative positions of the conjoined elements in angularly disposed planes, thereby facilitating the positioning of the pulley in a mounting frame, and the movement of the structural elements of its housing 40 into frictionally maintained clamping relation therewith.

8. A sash pulley comprising a sheave, a housing member, to which said sheave is journaled, adapted to fit into a recess in a 50 window frame, and provided with means to engage the forward face of the frame to limit the movement of said member in one direction into said recess, and with means to sustain the thrust of said housing member 55 against the end of said recess, and a hood member, carried by and movable relative to said housing member, to releasably engage the rear face of the frame and lock said housing member to the frame irrespective 60 of a considerable range in thickness of said frame.

9. In a sash pulley, a sheave, a housing member having rearwardly and forwardly facing engaging faces to engage, respectively, the front and rear faces of a window

frame member to prevent its inwardly and outwardly displacement upon coming to operative position therein, means, carried by and coactive with the housing member, to engage the rear face of the frame member 70 and adapted to penetrate and embed therein to a greater or less extent as may be required by the thickness of the particular frame member engaged, to lock the housing member to the frame member, and means to 75 hold the housing member and pulley in locked relation to said frame member.

10. In a sash pulley, the combination with a sheave, of a housing, comprising a pair of elements constituting, respectively, a support and a hood for the sheave, movably connected in frictionally resistant, relatively movable relation and adapted to co-operatively move into securing engagement with a window frame member through the 80 impelled movement of one of said housing elements into backwardly forcing engagement with the rear face of said frame member, whereby the housing and pulley may be positioned in said frame member and secured therein by a frictionally maintained engagement of the structural elements of 85 said housing.

11. In a sash pulley, the combination with a sheave, of a housing comprising a pair of 90 members constituting, respectively, a supporting member, provided with a rearwardly facing face to engage the forwardly facing face of a window frame member, to limit the movement of the supporting member, in 100 one direction, into a rout formed in the frame member for the pulley to seat in, and a hooding and securing member, provided with forwardly facing faces to engage the rear face of the frame member to clamp the 105 supporting member to said frame member, and means for movably uniting the said housing members in relatively mobile and frictional relation, whereby they are adapted, by the impelled movement of the hooding 110 member, to co-operatively move into penetrating and clamping engagement with the window frame member, into the rear face of which, the forwardly facing face of the hooding member may penetrate, and become 115 embedded to a greater or less extent as may be required by the thickness of the particular frame member engaged, to bring the housing members, relatively, into proper locking position, and facilitate securing the 120 pulley in window frame members of relatively variable thickness, by a frictionally maintained engagement of the structural members of the housing.

12. In a sash pulley, a sheave, a sheave 125 housing comprising two members, constituting, respectively, a support and a hood for the sheave, means for connecting said housing members, relatively, in mobile relation, whereby the said housing members are 130

adapted to move into engagement with a frame member through the relative movement of said housing members in response to the impelled movement of one of them, 5 thereby to clamp and secure the housing and pulley in said frame member, and means carried by said housing members to maintain them in the relative position assumed for securing the housing and pulley in said frame 10 member.

13. In a sash pulley, the combination with a sheave of a housing, comprising a supporting member, to which the sheave is journaled, adapted to seat in a rout formed in a 15 mounting frame, and having a centrally apertured face plate, a rearwardly facing engaging face to coöperate with the forward side of the mounting frame to limit the movement of said supporting member, in 20 one direction, into the rout in said mounting frame, a base to sustain the thrust against the end of said rout, and side walls to support the sheave axle, and an individual hooding and securing member, carried by and 25 movable relative to the said supporting member, comprising a hollow shell having an open front and rear for the unobstructed passage of the sheave, when rotating within it, and boundary walls presenting forwardly 30 facing, terminally beveled edges to engage and penetrate, with a backwardly wedging tendency, the rear side of the mounting frame, and embed therein to a depth variable in correspondence with the thickness of 35 the particular mounting frame engaged, to clamp the said supporting member to the mounting frame selected irrespective of a relatively wide range in thickness of such frames, and means, carried by the housing 40 members to relatively lock and maintain them in clamped relation with the mounting frame.

14. In a sash pulley, the combination with a sheave of a housing comprising a supporting and a hooding member, the former having rearwardly, and the latter forwardly facing frame engaging faces to coöperate, respectively, with a front and a rear face of a mounting frame in clamping and embedding engagement, said housing members being assembled in relatively movable relation with their frame engaging faces, respectively, facing toward one another in variable spaced relation, and adapted to assume 50 a variety of changes in relative position, thereby to increase and diminish the relative distances by which the frame engaging faces of the respective members are spaced apart relative to the direction of the particular 55 movement of the member through which the change in relative position of the conjoined members is effected, whereby the said housing members may be relatively positioned to facilitate inserting the housing in a rout in 60 the mounting frame and bringing said hous- 65

ing to seated position therein with the frame engaging faces of its respective members properly positioned for movement into clamping and embedding engagement, respectively, with the front and rear face of 70 the mounting frame, to secure the housing and pulley therein by the clamping of said mounting frame between said housing members.

15. In a sash pulley, the combination with 75 a sheave, of a housing embodying a supporting element comprising a front plate having an opening for the passage of the sheave, a rearwardly facing face for engagement with the outer side of a mounting 80 frame to arrest the inward passage of the element upon its coming to position in said frame, a base for it to seat upon and rearwardly extending side walls to receive and support an axle upon which the sheave is 85 rotatably mounted, and an extendible element, mounted coaxially with the sheave in the supporting element and adapted for limited movement therein, comprising a pair of units slidably assembled in frictionally re- 90 sistant telescopic relation, forming a hollow shell for the free passage of the sheave when rotating within it and having positioned upon its boundary walls forwardly facing 95 faces to engage the inner side of the mounting frame in backwardly wedging and penetrating engagement, the relation being such, that the extendible element may be collapsed, the pulley inserted in the mounting frame and the elements of the housing re- 100 spectively brought into proper clamping engagement with the inner and outer side of the mounting frame, to secure the pulley therein by drawing out the telescopically assembled extendible element into friction- 105 ally maintained extended position.

16. In a sash pulley, a sheave, journaled in a housing, embodying a supporting element comprising a centrally apertured front plate, a rearwardly facing face for engagement with a forwardly facing face of a mounting frame to arrest its inward passage upon coming to position therein, a base for it to rest upon and inwardly extending side walls to support the sheave axle, said walls 110 being provided with runways having forwardly facing bottoms, and a second element, a hollow shell like structure, within which the sheave may rotate unobstructedly, comprising a pair of side walls, connected 115 at their upper ends by a cross wall to form a hood for the sheave, adapted for sliding confinement within the runways of the supporting element and having front edges adapted to engage with the inner side of the 120 mounting frame and to embed therein more or less deeply, relative to the measure in thickness of the mounting frame engaged, and a detent, carried by one of the housing 125 elements adapted to engage successively the 130

teeth of a ratchet, carried by the other of said elements, whereby the pulley may be seated in a mounting frame and locked in clamped engagement therewith with the side walls of the second element wedged between the bottoms of the runways of the supporting element and the inner side of the mounting frame.

17. In a sash pulley comprising a sheave, 10 a housing member serving as a journal support for the sheave, and a relatively mov-

able housing member serving as a hood for the sheave, the embodiment of means, adapted in coöperation with said housing members to lock the housing and pulley to a 15 mounting frame.

In testimony whereof I hereunto affix my signature this 29th day of January, 1920.

JAMES H. FOOTE.
